UNITED STATES PATENT OFFICE.

NEWTON H. TRAVER, OF DETROIT, MICHIGAN.

CARPET-EXHIBITOR.

SPECIFICATION forming part of Letters Patent No. 417,608, dated December 17, 1889.

Application filed August 2, 1889. Serial No. 319,551. (No model.)

To all whom it may concern:

Be it known that I, NEWTON H. TRAVER, of Detroit, in the county of Wayne and State of Michigan, have invented a new and Improved Carpet-Display Rack, of which the following is a full, clear, and exact description.

My invention relates to an improvement in display-racks for carpets, oil-cloth, shade-cloth, &c., in salesrooms, and has for its object to provide a device of simple and durable construction to which the material may be attached in rolls drawn from the device in lengths as required for display or sale and automatically rewound when desired.

A further object of the invention is to provide a means whereby less floor-room will be required for the display of the goods, and wherein the rolls will require handling but once, and also wherein a maximum amount of vertical space may be utilized.

The invention consists in the novel construction and combination of the several parts of the device, as will be hereinafter fully set forth, and pointed out in the claims.

Reference is to be had to the accompanying drawings, forming a part of this specification, in which similar figures and letters of reference indicate corresponding parts in all the views.

Figure 1 is a front elevation of the device. Fig. 2 is a horizontal section through the supporting-beams, the device being shown in plan view. Fig. 3 is a side elevation. Figs. 4 and 5 are detail views of the rewinding mechanism, and Figs. 6 and 7 are detail perspective views of portions of the brackets. Fig. 8 is a plan view of a slightly-modified form of the device. Fig. 9 is a vertical section through the rewinding mechanism of the same. Fig. 10 is a side elevation of the rewinding mechanism; and Fig. 11 is a side elevation of one bracket detached.

The standards 10, adapted to support the device, are preferably made in girder shape or of I-bars provided with ratchet-notches 11 upon one face in the edges of their flanges, the said standards being introduced at the base into short sockets 12, secured to the floor and into long sockets 13, attached to the ceiling, whereby the standards may be readily adjusted to rooms of varied or vary-

ing heights. The standards are arranged at suitable distances apart and in horizontal alignment, and upon the flanges of each 55 standard a bracket is held to slide, two brackets 14 and 15 forming a portion of each device. The brackets are essentially alike in construction, each bracket comprising a body portion *a*, having an outwardly-extending 60 arm *a'* integral with the lower end, the upper portion *a*² being considerably wider than the surface immediately above the arm. At top and bottom of the rear edge of the body an essentially L-shaped lug 16 is cast, extending inwardly and vertically beyond the edges, and a perpendicular rib 17 is formed upon the inner end of the arm *a'*, and in the upper portion of the body an opening 18 is produced, surrounded at the bottom and sides 70 by an essentially U-shaped flange 19, having inclined inner faces, the inner perpendicular member whereof is in a vertical plane with the arm-rib 17. (See Figs. 3 and 6.)

The inner surface of the bracket-bodies between the lugs 16, the rib 17, and aligning member of the U-flange 19 is adapted to slide upon the outer face of the standard-flanges, and when in this position they are held to place by the lugs 16 contacting with the inner faces of the standard-flanges at the rear, and a key 20, introduced into the bracket-opening 18, contacts with the corresponding face of the standard-flange at the front, or that portion of the flanges containing the notches 11, as shown in Fig. 3. The key 20 is illustrated in detail in Fig. 7, and comprises a body *b*, of suitable shape to slide over the opening 18 into the U-flange 19, and when in this position it is wedged to place, an offset *b'*, integral with the lower end, fitting over the flange, and a rearwardly-extending finger *b*² contacting with the notched standard-flanges, as aforesaid. The lugs 16 are first made to contact with the standards, and then 95 the key is inserted.

It is obvious from the foregoing description that the brackets may be expeditiously and conveniently detached from the standards whenever desirable by removing the key. The 100 brackets are locked to the standards at various points in the height of the latter by pawls 21, weighted at their forward ends, one of which pawls is pivoted upon the lower por-

tion of the section a^2 of each bracket immediately beneath the U-flange 19, as shown in Fig. 3, and enters the notches 11 of the standards. The weighted ends of the pawls serve to retain the inner ends in normal engagement with the standards and also afford a handle for disengaging the pawls.

In the upper edges of the section a^2 of the left-hand bracket 15 a recess 22 is produced, which recess is adapted for the reception of one end of a reel-shaft 23, the bearing for this end of the shaft being completed by pivoting to the inner face of the bracket a lock-lever 24, recessed in that portion of the lower edge spanning the recess 22, as shown in Fig. 12. The lock-lever is limited in its downward movement by a stirrup 25, integral with the bracket, and is normally retained in contact with said stirrup by a spring 26, as shown in Fig. 1, which spring also acts as a brake to prevent the revolution of the reel-shaft unless the same is properly revolved. The bracket 14 differs only from the bracket 15 in that the lever 24 and stirrup 25 are omitted, and the body projection a^2 is higher and provided with a circular opening for the reception of the reel-shaft, and a rear projection a^3 is integral with the top of the body, as shown in Fig. 3. The reel-shaft 23, journaled in the brackets, is provided at the left-hand end with two or more annular grooves 27, adapted to receive the lock-lever, whereby the shaft may be shifted from right to left, and vice versa, and held in the shifted position.

Upon the shaft 23, between the brackets at the right-hand end, a spur-wheel 28 is secured, and at each side of the center a disk 29 is adjustably mounted upon the shaft, provided with a series of pins 30 upon the inner face, between which disks the roll of carpet, oil-cloth, or other material is held, the pins entering between the folds.

Upon a spindle secured to the inner face of the right-hand bracket a^3 a drum 32 is loosely mounted, containing a coil-spring 33, as shown in Fig. 5, one end of which spring is attached to the spindle and the other end to the inner peripheral face of the drum. Upon the outer edge of the periphery of the said drum a series of teeth 34 are formed, adapted to mesh with the spur-wheel 28 of the reel-shaft, and upon the outer face of the drum a pawl 35 is pivoted, having projected from opposite sides of its head horns 36, as shown in Figs. 4 and 5, adapted to be engaged by a strap-spring 37.

Upon the inner face of the rear projection a^3 of the bracket 14 an arc-shaped projection 38 is formed, the concave edge being upward, and upon this edge a series of ratchet-teeth 39 are produced, as shown in dotted lines, Fig. 3, and in section, Fig. 5. The pawl 35 of the drum during a portion of the revolution of the latter contacts with the ratchet-teeth.

The operation is as follows: When the carpet is drawn downward to unroll the same,

the pawl being in the normal position illustrated in Fig. 3, the drum is, by meshing with the reel-shaft gear 28, forwardly revolved, thereby winding up the spring, and as the pawl approaches the ratchet-teeth 39 it is thrown in position to contact with said teeth, as illustrated in Fig. 4, by the spring 37 acting upon one of the horns, whereby, while so contacting, if the reel-shaft ceases to revolve the drum will be locked in position. If the drum continues to revolve until the pawl passes the toothed arc 38, the spring 37, pressing forward against the upper horn 36, restores the pawl to its normal position, whereby, if the hold upon the carpet is released at this point, the expansion of the drum-spring 33 acts to turn the drum rearward, the pawl offering no resistance, as shown in Fig. 5. This latter movement of the drum rewinds the carpet upon the roll. It is necessary to guide the carpet in rewinding, and to that end a guide-shaft 40 is journaled upon the arms a' of the brackets and provided with a movable sleeve 41, which sleeve is brought in alignment with one of the disks 29, preferably the right-hand one.

Two or more devices may be placed upon each set of standards, one above the other, and the device is so proportioned that when the brackets contact with the floor a roll of carpet having the reel-shaft inserted may be placed in position without being lifted. After one roll has been placed in the device the latter is elevated as high as desired, and the next device is attached to the standards, &c. If an upper roll is sold before the lower one, the brackets of the upper devices are removed, the lower rolls elevated, and the brackets again attached to the standards at the bottom.

The form of device illustrated in Fig. 8 is especially adapted for oil-cloth and similar goods which do not require to be drawn off the roll in such lengths and which do require considerable power applied to rewind. In this construction the drum is mounted upon a sleeve 41^a, through which the reel-shaft passes, which sleeve is a portion of the bracket, as shown in Fig. 9, and a clutch-section 42 is formed upon the inner face of the drum for contact with a similar section 43 upon the hub of the spur-wheel 28, and the arc-ratchet projection 38 is produced upon the forward extension a^2 of the bracket, as shown in Fig. 10 of the drawings.

If found desirable, the bracket 14 may be constructed in every instance with the sleeve 41^a and an arc-shaped projection upon the inner face of both the front and rear extensions a^2 and a^3 , in order that the device may be used interchangeably for carpets and oil-cloth or similar material by removing the drum from front to rear, and vice versa.

When it is desired to unroll quite a length of material, a sale having been made, for instance, in either construction shown the drum may be thrown out of gear with the reel-shaft

by raising the lock-lever 24, sliding the reel-shaft to the left, and carrying the lever over out of the groove 27. When shifting the shaft, in order that it may not be carried too far to the left and thereby draw the right-hand end from its bearing, an angle-arm b^4 is formed upon one of the keys, which limits the shifting movement of the shaft by contacting therewith. This angle-arm may also be utilized as a handle to facilitate the removal of the keys.

Having thus fully described my invention, I claim as new and desire to secure by Letters Patent—

15 1. In a display rack for carpets and similar goods, the combination, with standards and brackets held to slide upon said standards, of a reel-shaft journaled in the brackets and a spring-controlled drum connected with said 20 shaft, substantially as described.

2. In a display-rack for carpets and similar goods, the combination, with standards and brackets held to slide upon said standards, of a reel-shaft journaled in the brackets, 25 disks adjustably attached to the shaft, and a spring-controlled drum connected with the shaft, substantially as and for the purpose specified.

3. In a display-rack for carpets and similar goods, the combination, with standards and brackets detachable from and adjustable upon the standards, of a shaft journaled in said brackets, disks adjustably attached to the shaft and provided with pins upon their 35 opposed faces, a spring-controlled drum connected with the shaft, and means, substantially as described, for laterally shifting the shaft, as and for the purpose specified.

4. In a display-rack for carpets and similar 40 goods, the combination, with standards having notched flanges, brackets capable of sliding upon the standards, and pawls pivoted upon the brackets adapted to enter the notches of the standards, of a shaft journaled in said brackets, toothed disks adjustably attached to the shaft, a spring-controlled drum connected with the said shaft, and a guide-shaft also journaled in the brackets below and in front of the disk or reel-shaft, substantially as shown and described.

5. In a display-rack for carpets and similar 45 goods, the combination, with standards, brackets capable of sliding upon the same, one bracket being provided upon its inner face with a segmental rack projection, and a reel-carrying shaft journaled in said brackets, of

a drum connected with the shaft and provided with a controlling interior coil-spring, a pawl pivoted upon one side of the drum, having horns at its head, and a spring adapted to 60 bear alternately upon the horns, whereby the movement of the pawl over the segmental rack is controlled as the drum is revolved, substantially as specified.

6. The combination, with a drive-shaft and its bearings, one of said bearings being provided with a segmental toothed projection, of a drum connected with the shaft and provided with an interior controlling coil-spring, a pawl pivoted upon one side of the drum and 70 adapted to contact with the said toothed projection, horns radiating from opposite sides of the pawl-head, and a strap-spring attached to the drum capable of alternately contacting with the opposed horns of the pawl, substantially as specified.

7. In a device for exhibiting carpets and similar goods, the combination, with standards having notched flanges, of brackets held to slide upon said standards, comprising a 80 body capable of contact with the side of the standards, an arm projected from the bottom of the body, essentially L-shaped lugs integral with the top and bottom of one side edge of said body and capable of clamping one side 85 flange of said standards, a detachable key sliding in the body, having a projecting finger capable of clamping the other flange of the standards, and a locking-pawl pivoted upon the body, substantially as shown and de- 90 scribed.

8. In a device for exhibiting carpets and similar goods, the combination, with standards having notched flanges, of a bracket held to slide upon the standards, comprising a 95 body provided with a recess in its upper edge and capable of contact with one side edge of the standards, an arm projected from the bottom forward edge of said body, essentially L-shaped lugs integral with the top and bottom 100 of the body at its rear edge, a locking-lever crossing the body-recess, a key detachably secured to the body and provided with a clamping-arm and a crank-arm extending upward in front of the body-recess, and a gravity- 105 pawl capable of entering the notches of the standard, substantially as shown and described.
